UNITED STATES PATENT OFFICE.

JOHN H. GEORGE, OF PHILADELPHIA, PENNSYLVANIA.

SAFETY-PLUG LOCK FOR GAS COCKS.

Application filed July 31, 1923. Serial No. 654,800.

My invention relates to safety locks for holding gas cock valves in closed position to avoid accidental or unauthorized opening.

The main purpose of my invention is to support the lock wholly upon the valve member of the gas cock so that interchange of the valve members will supply the lock to existing valves not previously so supplied.

A further purpose is to free the gas cock body and line from all support for the locking device.

A further purpose is to lock against the body of the gas cock instead of against the pin in the valve element.

A further purpose is to reduce the size of the locking parts.

A further purpose is to guide the lock in straight line movement transverse to the direction of locking strain.

A further purpose is to spring press the lock so as to move radially to locking position and to utilize the snap of the lock as a check to verify movement to complete the locking position.

Further purposes will appear in the specification and in the claims.

I have preferred to illustrate my invention in several slightly different forms, selecting forms which are practical, inexpensive and commercially very desirable and which at the same time well illustrate the principles of the invention.

Figure 1 is a perspective showing a gas stove having cocks equipped with my lock.

Figure 2 is an enlarged side elevation of one of the cocks seen in Figure 1, locked to closed position.

Figure 3 is a front elevation of the structure of Figure 2, the valve being locked in closed position.

Figures 4 and 5 are sections respectively upon the lines 4-4 and 5-5 of Figure 2.

Figure 6 shows a detail in perspective.

Figure 7 is a side elevation of the structure of Figure 2, the valve being open.

Figure 8 is a section taken along the line 8-8 of Figure 7.

Figure 9 is a perspective of a modified form.

Figures 10 and 11 are broken partly sectional elevations of other forms.

In the drawings similar numerals indicate like parts.

Describing in illustration and not in limitation and referring to the drawings:-

My gas cock lock is intended for use in

such locations as in Figure 1 where a gas stove 6 is equipped with separate gas cocks 7 for each of a number of different burners.

The body 8 of the gas cock is or may be the same as any of the commercial gas cocks upon the market at the present time, having an inlet 9 connected by thread 10 with the inlet pipe and a discharge 11 of reduced diameter intended to discharge within a sleeve 12 so that air may be injected along with the gas as is common in all such burners.

Between the inlet and the discharge lies the movable valve element, which, so far as the valve function is concerned, is identical with existing valve plugs for such gas cocks now on the market. It has the usual tapered body 13 adapted to fit into a tapered gas cock opening 14 and its lower end is extended to receive a screw 15 at sufficient distance from the gas cock body to give room for a tightening spring 16. The spring surrounds the gas cock extension and presses against washers 17 and 18. At the upper end the plug is provided with a stop pin 19 which permits opening and closing turning movement of the valve but in which engagement of the pin with the terminal walls 20 and 21 of a recess 22 in the body of the plug limits the opening and closing movements respectively of the plug.

As thus far described the plug is typical of those generally in use with gas stoves.

By my invention I mount a locking element upon the plug to turn with the plug and adapted to latch into the recess when the valve is closed. This prevents rotation of the plug from position of closure unless the latch is sprung back. I find that it is not necessary to provide any special lock or projection upon the gas cock body for this locking engagement as the wall 20 of recess 22 may be used for this purpose.

In the embodiment shown the lock comprises a yoke 23 carrying a "lock" in the form of a projection 24 for latching engagement with the wall 20. The yoke is mounted upon the plug to turn with it and is operated in one direction by a spring to locking position. When pressed inwardly by the spring it latches against the wall 20 and for release is pressed by the thumb of the operator until it lies radially beyond this wall so that the plug and locking element (yoke) carried by it may turn without engagement of the lock against the wall 20.

The elements which I utilize for my latch

are primarily the latch nose or lug itself, a mount for it, a guide for its movement (which may be included in the mount) and means for holding the lug in latching position and preferably spring pressing it toward this position. The yoke is convenient, whether open at one end or closed at both ends, because its sides assist in the guiding function and the lug is carried by the front 10 of the yoke. To support the yoke I provide a transverse pin 25 passing through an opening 26 in the plug which opening is counterbored at 27 (except in the Figure 11 form) to give room for a spring 28 pressing 15 against the shoulder 29 of the counterbore and against the shoulder 30 upon the pin.

The pin, preferably made rigid with the yoke, functions to lock the yoke from turning about the plug, while permitting the 20 yoke to be sprung transversely of the plug. It is held in position with respect to the front 30 of the yoke by any suitable means as by a reduced end riveted in place as at 31.

The downwardly extending latch projection or lug 24 is preferably curved to agree 25 substantially with the contour of the outer surface 32 of the body of the cock so that, when the valve is not closed, the projection rides along the outside of the gas cock 30 surface while the plug is turned, being pressed against this surface by the spring 28.

When the plug is turned to closed position, the spring snaps the latch into the recess 22 from the edge 33 of the surface of the 35 gas cock body and against the body of the plug. The sound from this snapping home of the latch affords a convenient check as to complete closure of the valve and is noticeably increased by the use of aluminum, for 40 example, as the metal, as compared with brass.

Opposite sides of the yoke preferably fit 45 and slide along the plug at 34 to guide the latch at the sides as it moves and to support it against side strain. I prefer to have this portion of the plug cylindrical instead of tapered so that the sides of the yoke may not have to taper at this section.

The yoke structure with the lock carried 50 by it affords a transverse locking plunger in which the side walls of the yoke act to guide the movement of the locking member maintaining it from turning upon the pin, and also improve the appearance of the 55 structure.

The yoke is preferably closed; i. e., its sides extend all the way round. The sides are inwardly flanged at 35 to move within a groove 36 in the plug member to support the 60 yoke against movement axially of the plug.

The valve stem is provided with the usual handle 37 and the yoke is conveniently finished by a button 38 mounted upon the pin for a thumb press.

Obviously it makes no difference whether

the thumb pressure be exerted against the button 38 or against the yoke or other member serving the guiding and supporting purpose for which the yoke is provided. Where the yoke is open at one end as in Figure 70 9 the button 38 is of greater utility than in such figures as 2 and 7 but it may be wholly omitted as in Figure 10.

The upper part of the valve element carrying the handle is preferably made as a 75 sleeve 39 secured to a reduced valve stem 40 in order to conveniently provide the groove 36. The sleeve is fastened to the stem as by pin 41.

In assemblage the yoke is placed over the 80 stem of the valve and the sleeve 39 is fastened in place upon the stem. The pin 25 is then passed through the spring 28 and the two together are inserted from the left in such a figure as Figure 8. The pin 85 31 is riveted at 31 in position. The button 38 may have been placed before insertion of the pin 25 or may be put on afterward.

The plug element with its assembled latch can readily be sold as a unit to fit existing 90 gas cock bodies, the valve element being substituted for the valve element originally supplied with the gas cock, this requires but a few moments for substitution and involves no disconnection of pipes and a minimum of 95 trouble and expense.

To open the valve the thumb of the user is pressed against the button 38 or against the yoke to overcome the spring pressure 100 and to force the latch out far enough for the valve element to be turned. The valve is then turned.

It will be obvious that the yoke member forms a latch spring pressed transversely toward the plug, riding along the outer surface of the body except at the position of closure when it snaps to place in the recess and against the plug locking the plug from turning unless and until the latch has been pushed back out of the recess.

In the form of Figure 9 the yoke is open, that is, does not go all the way around the plug. The length of the pin and yoke is limited by its range of transverse travel for latching. When the latch projection is riding along outside of the body the front end of the pin may extend only a very little beyond the plug.

In the forms of Figures 10 and 11 the push buttons are omitted and the pin 42 of 120 small diameter surrounded by the spring extends through the plug to opposite outer surfaces of the yoke. In Figure 10 the plug is counterbored to receive the spring 28. A short sleeve 43 upon the pin fits into the 125 counterbore to provide proper guide bearing between the yoke member and the plug and to suitably compress the spring.

In Figure 11 the spring is placed outside 130 of the plug, avoiding the need for sleeve and

counterbore but necessitating a somewhat longer yoke by reason of the length of the spring even when compressed. In this form the inward flange 35 at the top of the yoke has also been omitted, the opposite sides of the yoke member together with the pin serving the guiding function. The yoke fits along opposite sides close to the plug. In Figure 11 I have also made the latch of size 10 to fit all the way across the recess, above the usual stop pin shown in the other figures.

In the forms shown I have preferred to use one side of the usual recess 22 for a stop-catch for the latch. Essentially however this catch is any lateral stop rigid with the body and adapted to cooperate with the spring latch.

Obviously these forms are all broadly the same invention.

20 It will be obvious that those skilled in the art will, in view of my disclosure, see various other modifications and changes which may be made in my structure to secure the benefit of all or part of the invention without copying the forms, shown; and it is my purpose to include herein all such as come within the reasonable spirit and scope of my claims.

Having thus described my invention, what I claim as new and desire to secure by Letters Patent is:—

1. In a gas cock valve, a valve body having a recess in its upper end, a valve member movable in said body, a pin in the valve member limiting movement of the valve by engagement with a wall of the recess and a fastening device carried by the valve member, comprising a spring pressed pin passing through the valve member and a lock carried by one end of the pin, enclosing the valve element and pressed by the spring toward position for engagement with a wall of the recess, the lock being adapted to fill in the space between this wall of the recess and the pin in the closed position of the valve and for thumb engagement to release it.

2. In a gas cock valve, a valve body having a recess in its upper end, a valve member in said body, a pin in the valve member limiting movement of the valve by engagement

with a wall of the recess and a fastening device carried by the valve member, comprising a pin passing through the valve stem transversely, a spring within the valve stem pressing against a portion of the pin and a lock carried by the pin, enclosing the valve element and adapted in locked position to stop against a wall of the recess and against the pin in the valve and a thumb press connected with the other end of the pin for release of the lock.

3. In a gas cock valve, a valve body having a recess in its upper end, a valve member movable in said body, a pin in the valve member limiting movement of the valve by engagement with the walls of the recess and a fastening device carried by the valve member, comprising a movable pin, passing through the valve stem and spring pressed rearwardly, a yoke carried by the pin, enclosing the valve element and guided at its sides by the stem and a lock upon the yoke engaging in one position with a wall of the recess and with the pin in the valve member.

4. In a gas cock valve, a valve body having a recess in its upper end, a valve member movable in said body, a pin in the valve member limiting movement of the valve by engagement with the walls of the recess and a fastening device carried by the valve member, comprising a spring pressed pin movable transversely with respect to the valve stem, a yoke upon the pin, enclosing the valve element and guided at its sides by the stem, a lock upon the yoke to occupy the space in said recess exclusive of the pin upon the valve member and flanges upon the yoke passing within a groove in the stem and guided by the walls of the groove.

5. In a gas cock lock, a gas cock body having a lateral abutment, a valve member lying within the body and having stop pin engagement with the body to limit its movement and a transversely movable lock carried by the valve member, guided by it against rocking and axial movements, spring-pressed and engaging the abutment and stop pin in one position.

JOHN H. GEORGE.
